CLAIM

The ornamental design for a front face of a molding, as shown and described.

DESCRIPTION

FIG. 1 is a perspective view of a front face of a molding, in accordance with our new design, shown on a table for convenience of illustration; the broken lines are for environmental purposes only and form no part of the claimed design;

FIG. 2 is an enlarged front elevational view of the front face of a molding, broken in the center to disclose indeterminate length;

FIG. 3 is an enlarged side view thereof, the opposite side being a mirror image thereof; and,

FIG. 4 is an enlarged perspective view thereof and broken in the center to disclose indeterminate length.
